(Cl. D61—1)

FIG. 1.

FIG. 2.

Fig. 1 is a front perspective view of an X-ray unit showing our new design; and

Fig. 2 is a fragmentary front perspective view showing portions of the unit disclosed in Fig. 1 with the panel on the control member in closed position.

The undisclosed portions of the control unit are substantially plain.

The essential features of our design reside in the solid line portions.

We claim:

The ornamental design for an X-ray unit, substantially as shown and described.
